L. V. GELDER

HOT WATER HEATER

Filed Nov. 26, 1920

Inventor
Leo V. Gelder.

By Harry D. Schroeder
Attorney

UNITED STATES PATENT OFFICE.

LEO V. GELDER, OF OAKLAND, CALIFORNIA.

HOT-WATER HEATER.

Application filed November 26, 1920. Serial No. 426,481.

To all whom it may concern:

Be it known that I, LEO V. GELDER, a citizen of the United States, residing at Oakland, in the county of Alameda and State 5 of California, have invented certain new and useful Improvements in Hot-Water Heaters, of which the following is a specification.

My invention is an improved hot water 10 heater particularly useful for heating a domestic boiler and a hot water radiator system either together or independently of each other.

My invention is illustrated in the annexed drawing which forms a part of this specification.

The figure in the drawing is a vertical section of my heater applied to a domestic boiler and a hot water radiator system.

20 My heater includes two water heating chambers 1 and 2 and two burners 3 and 4 located respectively adjacent said chambers. The chamber 1 is formed with a vertical member 5 and a horizontal member 6 extending outwardly from the upper end of said vertical member. The chamber 2 is formed with a vertical member 7 and a horizontal member 8 extending outwardly from the upper end of the member 7. The chambers 1 and 2 are arranged with their inner sides facing each other and at a short distance apart. The chambers 1 and 2 and the burners 3 and 4 are mounted in the lower open end of a domestic boiler 10, the bottom wall 11 of said boiler being located above the lower end thereof and just above the chambers 1 and 2. The burner 3 is located near the outside of the vertical member 5 and under the horizontal member 6 of the chamber 1. The burner 4 is located

near the outside of vertical member 7 and under the horizontal member 8 of chamber 2. The burners 3 and 4 have shields 12 and 13 for shielding the flames of the burners from water dripping from the horizontal members 6 and 8 of the chambers 1 and 2. A water supply tube 14 extends through the wall of the boiler 10 below the bottom wall 11 and connects to a tube 15 extending upwardly into the lower end of the vertical member 5 of the chamber 1. A cap 16 screws onto the lower end of the tube 15. A tube 17 extends from the top of the chamber 1 through the bottom wall 11, into the boiler 10 to a point near the top thereof. A pipe

18 is connected to the lower end of the vertical member 7 of chamber 2 and to a radiator 20. A water supply tube 21 is connected to the pipe 18. A pipe 22 connects the lower parts of the radiators 20 and 25 and 60 is connected with the horizontal member 8. A pipe 26 leads from the radiator 25 and connects to the radiator 20. A tube 30 extends centrally through the boiler 10 from the bottom wall 11 just above the space between the vertical members 5 and 7 of the chambers 1 and 2 which tube provides a draft for the burners 3 and 4 which heat the water in the boiler.

Both burners 3 and 4 may be used to 70 heat the water in the boiler 10 or the burners 3 or 4 may be used independently to heat the water in the boiler.

Having described my invention, I claim:

1. In combination with a domestic boiler 75 and a hot water radiator system, two water chambers located beneath said boiler, a burner located adjacent each water chamber, a tube leading from one of said water chambers into said boiler, a water inlet pipe 80 communicating with said water chamber and the other chamber being included in said hot water radiator system.

2. In combination with a hot water radiator system and a domestic boiler having a tube extending centrally therethrough, 85 two water chambers spaced apart and located beneath said boiler, the space between said chambers registering with the tube through said boiler, a burner for each chamber, 90 a tube extending from one of said chambers into said boiler, a water inlet pipe communicating with said chamber and the other chamber being included in said hot water radiator system.

3. In combination with a hot water radiator heating system and a domestic boiler, two water chambers located beneath said boiler, each chamber including a vertical member and an outwardly extending member 100 at the top of said vertical member, a burner for each chamber, a tube extending from one chamber into said boiler, a water inlet pipe communicating with said chamber, the other chamber being included in the 105 hot water radiator system.

4. In combination with a hot water radiator heating system and a domestic boiler having a tube extending centrally therethrough, two water chambers located be- 110

neath said boiler and spaced apart directly below said boiler tube, each chamber including a vertical member and a horizontal member extending outwardly from the top 5 of said vertical member; a burner for each chamber, a tube extending from one chamber into said boiler, a water inlet pipe communicating with said chamber and the other chamber being included in said hot water 10 radiator system.

5. In combination with a hot water radiator system, and a domestic boiler having a central vertical flue, two water chambers mounted beneath said boiler and spaced 15 apart at the center of said boiler, each water chamber including a vertical member and a horizontal member at the upper end of said vertical member, two burners located beneath said horizontal members respectively, 20 a tube extending upwardly from one chamber into the water compartment of said boiler, a water supply tube connected to said

chamber, the other water chamber being included in said hot water radiator system.

6. In combination with a hot water radiator system and a domestic boiler having a central vertical flue, two water chambers mounted beneath said boiler and spaced apart at the center of said boiler, each water chamber including a vertical member and a horizontal member at the upper end of said vertical member, two burners located beneath the horizontal members and substantially parallel with the vertical members of said water chambers respectively, a tube extending upwardly from one chamber through the bottom wall of the boiler into the water compartment of said boiler, a water supply tube for said chamber, the other water chamber being included in said hot water radiator system.

In testimony whereof I affix my signature.

LEO V. GELDER.
